(57) **CLAIM**

We claim the ornamental design for a chip for biochemical examination, as shown and described.

DESCRIPTION

FIG. 1 is a front perspective view of a chip for biochemical examination of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a rear perspective view thereof with the cover removed;

FIG. 10 is a rear view thereof with the cover removed;

FIG. 11 is a cross-section view taken along the line 11-11'-11" of FIG. 4 with the internal parts being omitted;

FIG. 12 is a cross-section view taken along the line 12-12 of FIG. 4 with the internal parts being omitted;

FIG. 13 is a cross-section view taken along the line 13-13 of FIG. 4 with the internal parts being omitted; and,

FIG. 14 is a cross-section view taken along the line 14-14 of FIG. 4 with the internal parts being omitted.
